COMBINATION PEN

Emilio Lasmarias Villarin, Waipahu, Oahu,
Territory of Hawaii

Application September 2, 1947, Serial No. 771,783

3 Claims. (Cl. 120—42.1)

1

This invention relates to fountain pens.

It is an object of the present invention to provide a fountain pen which is adapted for use by students and teachers and which has a multiple arrangement of pens and chambers for containing respectively different colored inks and wherein the pen can be readily adjusted to a position of use by the user depending upon the color desired.

Other objects of the present invention are to provide a multiple fountain pen arrangement which is of simple construction, easy to adjust, easy to fill with the different colored inks, inexpensive to manufacture, convenient to use and efficient in operation.

For other objects and for a better understanding of the invention, reference may be had to the following detailed description taken in connection with the accompanying drawing, in which

Fig. 1 is a top plan view of the fountain pen arrangement embodying the features of the present invention.

Fig. 2 is a side elevational view of the fountain pen.

Fig. 3 is a cross-sectional view, in elevation, taken generally on line 3—3 of Fig. 4.

Figs. 4 and 5 are respectively transverse cross-sectional views taken respectively on lines 4—4 and 5—5 of Fig. 2.

Referring now to the figures, 10 represents a hollow ring formation with hollow projections 11 extending radially therefrom at circumferentially spaced locations thereon. On these projections 11 there are respectively located pen points 12 over which covers 13 can be extended to protect the pen points when they are not in use. This hollow ring formation 10 is partitioned as indicated at 15 whereby to provide a plurality of arcuate shaped chambers 16 for containing the ink.

Extending upwardly and radially inwardly from the ring formation are arcuate shaped portions 17 having respectively passages 18 communicating with storage chambers 19. In these storage chambers 19, there are respectively disposed different colored inks. The ink will flow downwardly through the passages and will be delivered to the chamber 16. The flow from the chambers 19, however, is through an opening in which is threaded a valve element 21. The valve element may be screwed into and out of its respective opening to control the flow of ink to the chambers 16. The arcuate portions 17 are integral with a central hub 22 to the bottom of which there is connected for rotative adjustment relative thereto, a handle portion 23 adapted to

2

be adjusted for alignment with the pen point sleeves 11 and be secured to the ring formation 10 by set screws 24. To effect this connection through the hub 22, there is extended a shaft 26 having a head 27 embedded in the handle 23. On the upper end of the shaft 26 there is connected a nut 28 which is made preferably of flexible material so as to effectively close filling openings 29 through which the inks are poured to fill the chambers 16.

To put the pen into use, the nut 28 may be slightly loosened to permit the handle 23 to be adjusted to the particular pen point 12 to be used. With the handle 23 aligned as shown in Fig. 5 to the particular pen point and locked in position by screws 24, the handle can be grasped between the thumb and fingers and the writing done with the same. Ink will be supplied from the arcuate chambers 16 and should these chambers run dry other ink can be taken from the storage chambers 19 by releasing the valve element or screw 21. To render the handle portion 23 more comfortable, cavities or depressions 31 may be provided adjacent the ends of the same.

While various changes may be made in the detail construction, it shall be understood that such changes shall be within the spirit and scope of the present invention as defined by the appended claims.

I claim:

1. A multiple color fountain pen arrangement comprising a hollow ring formation having sleeve projections extending radially outwardly therefrom at circumferentially spaced locations thereon, pen points connected to the sleeve projections, said ring formations being hollow and partitioned to provide chambers for different inks, a structure extending upwardly from the ring formation and having a hub portion, a handle adjustably connected to the hub portion of the structure and adapted to be rotatably adjusted within the ring formation for alignment with the respective hollow sleeve projections having the pen points.

2. A multiple color fountain pen arrangement comprising a hollow ring formation having sleeve projections extending radially outwardly therefrom at circumferentially spaced locations thereon, pen points connected to the sleeve projections, said ring formations being hollow and partitioned to provide chambers for different inks, a storage chamber structure extending upwardly from the ring formation and comprising arcuate portions with passages therein, storage

chamber portions in communication with the passages of the arcuate portions and valve control means in the passages of the upwardly extending arcuate portions for controlling the passage of the ink from the storage chambers to the arcuate chambers of the ring formation.

3. A fountain pen arrangement as defined in claim 2, and said upwardly extending structure having a central portion, a handle pivotally connected to the central portion of the upwardly extending structure and depending therefrom and rotatably adjustable for alignment with the respective sleeve formations having the pen point, and means for locking the handle in its adjusted position.
